(57) **CLAIM**

The ornamental design for a stator for a vehicle rotary electric machine, as shown.

DESCRIPTION

This application is also related to U.S. patent application Ser. No. 29/309,962 filed simultaneously on Nov. 20, 2008 with the present application and entitled “Stator for a Vehicle Rotary Electric Machine”.

FIG. 1 is a front perspective view of a stator for a vehicle rotary electric machine showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

1 Claim, 8 Drawing Sheets
